US00D997264S

(12) **United States Design Patent** (10) **Patent No.:** **US D997,264 S**
(45) **Date of Patent:** **** Aug. 29, 2023**

(54) **ELLIPTICAL CYCLE**

(71) Applicant: **17 Thrasio Seventeen, Inc.**, Walpole, MA (US)

(72) Inventor: **Kevin Lawrence Colburn**, Windsor, CO (US)

(73) Assignee: **17 Thrasio Seventeen, Inc.**, Walpole, MA (US)

(**) Term: **15 Years**

(21) Appl. No.: **29/855,254**

(22) Filed: **Sep. 30, 2022**

Related U.S. Application Data

(63) Continuation of application No. 29/822,010, filed on Jan. 5, 2022, now Pat. No. Des. 970,653, which is a continuation of application No. 29/759,397, filed on Nov. 23, 2020, now Pat. No. Des. 943,038, which is a continuation of application No. 29/668,109, filed on Oct. 26, 2018, now Pat. No. Des. 906,445.

(57) **CLAIM**

The ornamental design for an elliptical cycle, as shown and described.

DESCRIPTION

FIG. 1 is a top perspective view of an elliptical cycle; FIG. 2 is a bottom perspective view of the elliptical cycle in FIG. 1;

FIG. 3 is a rear elevation view of the elliptical cycle in FIG. 1;

FIG. 4 is a front elevation view of the elliptical cycle in FIG. 1;

FIG. 5 is a first side elevation view of the elliptical cycle in FIG. 1;

FIG. 6 is a second side elevation view of the elliptical cycle in FIG. 1;

FIG. 7 is a top plan view of the elliptical cycle in FIG. 1; and, FIG. 8 is a bottom plan view of the elliptical cycle in FIG. 1.

The broken lines are included for the purpose of illustrating the unclaimed portions of the article and form no part of the claim.

1 Claim, 8 Drawing Sheets
